[57] **CLAIM**

The ornamental design for an artificial kidney assembly package with attached blood pump and multifunctional subassembly, as shown and described.

DESCRIPTION

FIG. 1 is a top perspective view of an artificial kidney assembly package with attached blood pump and multifunctional, subassembly showing my new design;

FIG. 2 is a front elevation thereof;

FIG. 3 is a right end elevation thereof;

FIG. 4 is a rear elevation thereof;

FIG. 5 is a left end elevation thereof;

FIG. 6 is a top plan view thereof; and

FIG. 7 is a bottom plan view thereof.
